CLAIM

The ornamental design for a collapsible enteral feeding container, as shown and described.

DESCRIPTION

FIG. 1 is a perspective view of a collapsible enteral feeding container showing my new design;

FIG. 2 is a front elevational view thereof, the rear view being a mirror image;

FIG. 3 is a right side elevational view thereof, the left side being a mirror image;

FIG. 4 is a top plan view thereof;

FIG. 5 is a bottom plan view thereof;

FIG. 6 is a perspective view thereof in collapsed condition;

FIG. 7 is a right side elevational view thereof in collapsed condition, the left side being a mirror image;

FIG. 8 is a front elevational view thereof in collapsed condition, the rear view being a mirror image;

FIG. 9 is a bottom plan view thereof in collapsed condition.

The top plan view of the container in collapsed condition is not shown and is essentially the same as the top plan view of the container in uncollapsed condition as shown in FIG. 4.
